(57) **CLAIM**

The ornamental design for a control handle for a material handling vehicle, as shown and described.

DESCRIPTION

FIG. 1 is a top, left, front perspective view of a control handle for a material handling vehicle embodying my new design;

FIG. 2 is a front elevational view thereof;

FIG. 3 is a rear elevational view thereof; and,

FIG. 4 is a left side elevational view thereof, the right side elevational view being a mirror image of the left side shown. The broken line representations of a tiller stem in FIGS. 1-4, of holes in FIGS. 1 and 3, and of holes for control elements in FIGS. 1-4, are for the purpose of illustration only, and form no part of the claimed design.
